US0D1091579S

(12) **United States Design Patent** (10) Patent No.: **US D1,091,579 S**
(45) Date of Patent: ** Sep. 2, 2025

(54) **DISPLAY SCREEN WITH A GRAPHICAL USER INTERFACE**

(71) Applicant: **Ferrari S.p.A.**, Modena (IT)

(72) Inventor: **Flavio Manzoni**, Modena (IT)

(73) Assignee: **FERRARI S.p.A.**, Modena (IT)

(**) Term: **15 Years**

(21) Appl. No.: **29/896,970**

(22) Filed: **Jul. 10, 2023**

Related U.S. Application Data

(62) Division of application No. 35/515,287, filed on Sep. 23, 2022 (U.S. filing date under 35 U.S.C. 384), and having an international filing date of Sep. 23, 2022, now Pat. No. Des. 1,016,843.

CLAIM

The ornamental design for a display screen with a graphical user interface as shown and described.

DESCRIPTION

The sole FIGURE is a front view of a display screen with a graphical user interface showing my design.

The short-dash broken lines show portions of the graphical user interface and form no part of the claimed design. The long-dash broken lines show a display screen and form no part of the claimed design.

1 Claim, 1 Drawing Sheet
